UNITED STATES PATENT OFFICE.

EDWIN S. MIX, OF ROCHESTER, NEW YORK, ASSIGNEE TO NORTH EAST ELECTRIC COMPANY, OF ROCHESTER, NEW YORK, A CORPORATION OF NEW YORK.

ELECTRIC CONNECTION.

1,405,185.

Specification of Letters Patent. Patented Jan. 10, 1922.

Application filed January 24, 1917. Serial No. 144,177.

To all whom it may concern:

Be it known that I, EDWIN S. MIX, a citizen of the United States, residing at Rochester, in the county of Monroe and State of New York, have invented certain new and useful Improvements in Electric Connections; and I do hereby declare the following to be a full, clear, and exact description of the invention, such as will enable others skilled in the art to which it appertains to make and use the same.

This invention relates to means for electrically connecting wires, strips, or other conductors, such as are employed in dynamo-electric machines and other electrical apparatus.

In dynamo-electric machines, and electrical apparatus of other kinds, it is frequently necessary to connect two conductors which meet or cross substantially at a right angle, and for this purpose the sleeves and similar devices which are commonly employed in making connections between conductors are not suitable. The object of the present invention, accordingly, is to provide means particularly adapted for making connections between such angularly-arranged conductors. To this end it is proposed to employ a connector consisting of a sheet-metal member having the form of a cross, this member being arranged with its body-portion interposed between the adjacent surfaces of the conductors, while the arms of the cross are bent in pairs around the respective conductors, the whole being preferably solidified by the use of solder between the adjacent surfaces of the conductor and the connector.

In the accompanying drawings Fig. 1 is a side-elevation of an electric connection formed in accordance with the present invention; Fig. 2 is a perspective view of the connection shown in Fig. 1; Fig. 3 is an end-elevation, partly in section, of a portion of the field-magnet assembly of a dynamo-electric machine in which the coils of the field-winding are connected in accordance with the present invention; and Fig. 4 shows the sheet-metal connector employed in the illustrated connection.

In Figs. 1 and 2 the invention is shown as employed in forming the connection be-

tween any two conductors 5 and 6 of similar cross-section, these conductors being relatively wide and flat and meeting, at their ends, at a right angle. In forming the connection a sheet-metal member in the form of a Geneva cross, as shown in Fig. 4, is employed. This connector comprises a central body-portion 7, a pair of oppositely disposed arms 8, and another pair of oppositely disposed arms 9. The body-portion 7 is interposed between the adjacent wide surfaces of the conductors 5 and 6, the arms 8 are then bent around the edges and against the outer surface of the conductor 5, and the arms 9 are bent similarly around the edges and the outer surface of the conductor 6. By means of this connector alone a joint is formed of considerable mechanical strength, and with a low electrical resistance due to the wide surfaces of contact, but for greater security and permanence the joint is preferably solidified by soldering together all of the meeting surfaces of the metal.

Fig. 3 illustrates the aspect of the invention in which it is particularly applicable to a dynamo-electric machine. In this machine the conductor 5 is shown as constituting the winding upon one of the four polar projections 11 of the machine, this winding being arranged so that the width of the metal in the conductor is parallel with the axis of the coil. The conductor 6 constitutes an intermediate conductor, for the purpose of connecting together the corresponding terminals of two successive coils. In this conductor the width of the metal is normal to the axes of the coils, and the ends are bent outwardly so as to lie parallel with, but at right angles to, the ends of the conductors 5, thus bringing the wide flat surfaces of the terminals and the intermediate conductor into parallel and proximate positions. The ends of the conductors are secured together in this position by means of connectors such as that of Fig. 4.

The invention claimed is:

1. In an electric connection, the combination of two wide and flat conductors arranged substantially at a right angle, with their wider surfaces parallel and overlapping; and a cross-shaped sheet-metal connector, of which the body-portion is inter-

posed between the adjacent surfaces of the conductors, and the arms are bent, in pairs, respectively around the two conductors.

2. In an electric connection, the combination of two wide and flat conductors arranged substantially at a right angle, with their wider surfaces parallel and overlapping; and a cross-shaped sheet-metal con-

nector, of which the body-portion is interposed between the adjacent surfaces of the conductors, and the arms are bent, in pairs, respectively around the two conductors; the whole being united by solder between the adjacent surfaces of the conductors and the connector.

EDWIN S. MIX.
